United States Patent [19]

Studer, Jr. et al.

[11] Patent Number: Des. 303,430

[45] Date of Patent: ** Sep. 12, 1989

[54] TRANSCUTANEOUS ELECTRICAL NERVE STIMULATOR

[75] Inventors: John E. Studer, Jr., Madison, N.J.; Joel R. Dufresne; Alan P. Dieken, both of St. Paul, Minn.

[73] Assignee: Minnesota Mining and Manufacturing Company, St. Paul, Minn.

[**] Term: 14 Years

[21] Appl. No.: 42,093

[22] Filed: Apr. 24, 1987

[52] U.S. Cl. D24/41; D24/36; D24/40

[58] Field of Search .... D24/41, 40, 36; 128/419 R, 419 P, 419 D, 421, 423

[57] CLAIM

The ornamental design for a transcutaneous electrical nerve stimulator, as shown and described.

DESCRIPTION

FIG. 1 is a perspective view of a transcutaneous electrical nerve stimulator showing our new design;
FIG. 2 is a rear elevational view thereof;
FIG. 3 is a left side elevational view thereof;
FIG. 4 is a right side elevational view thereof;
FIG. 5 is a front elevational view thereof;
FIG. 6 is a top plan view thereof; and
FIG. 7 is a bottom plan view thereof.
